US00D490104S

(12) **United States Design Patent**
Lubking

(10) **Patent No.:** **US D490,104 S**
(45) Date of Patent: **** May 18, 2004**

(54) **DATA CARD**

(75) Inventor: **Colleen C. Lubking**, Richmond, VA (US)

(73) Assignee: **Capital One Financial Corporation**, Falls Church, VA (US)

(**) Term: **14 Years**

(21) Appl. No.: **29/179,088**

(22) Filed: **Apr. 3, 2003**

(51) LOC (7) Cl. **19-08**

(52) U.S. Cl. **D19/10**

(58) **Field of Search** D14/435, 436, D14/437, 438; D19/9, 10, 11, 12; D20/40; 235/380, 382, 435, 436, 449, 454, 468, 469, 488, 491, 492, 493; 283/70, 72, 74, 75, 82, 99, 107, 904; 360/2; 428/916

(57) **CLAIM**

The ornamental design for a data card, as shown and described.

DESCRIPTION

FIG. 1 illustrates a perspective view of a data card, showing my new design;

FIG. 2 illustrates a front plan view thereof;

FIG. 3 illustrates a rear plan view thereof;

FIG. 4 illustrates a bottom elevational view thereof;

FIG. 5 illustrates a top elevational view thereof;

FIG. 6 illustrates a left side elevational view thereof;

FIG. 7 illustrates a right side elevational view thereof;

FIG. 8 illustrates an exploded plan view thereof;

FIG. 9 illustrates a perspective view of a data card, showing my new design;

FIG. 10 illustrates a front plan view thereof;

FIG. 11 illustrates a rear plan view thereof;

FIG. 12 illustrates a bottom elevational view thereof;

FIG. 13 illustrates a top elevational view thereof;

FIG. 14 illustrates a left side elevational view thereof;

FIG. 15 illustrates a right side elevational view thereof;

FIG. 16 illustrates an exploded plan view thereof;

FIG. 17 illustrates a perspective view of a data card, showing my new design;

FIG. 18 illustrates a front plan view thereof;

FIG. 19 illustrates a rear plan view thereof;

FIG. 20 illustrates a bottom elevational view thereof;

FIG. 21 illustrates a top elevational view thereof;

FIG. 22 illustrates a left side elevational view thereof;

FIG. 23 illustrates a right side elevational view thereof; and,

FIG. 24 illustrates an exploded plan view thereof.

The broken lines in the figures have been shown for illustration purposes only and form no part of the claimed invention.

1 Claim, 3 Drawing Sheets
